THREE DIMENSIONAL STAGGERED CHESS-
BOARD WITH MOVABLE SUPPORTS FOR
CHESSMEN

Christopher M. Culver, 1098 Leigh St., and Dale A. Lane,
2595 Pioneer Pike, both of Eugene, Oreg. 97401

Filed Oct. 6, 1971, Ser. No. 187,230

Term of patent 14 years

Int. Cl. D21—01

U.S. Cl. D34—5 SS

FIG. 1 is a perspective view of the three dimensional staggered chessboard with movable supports for chessmen embodying the present invention;

FIG. 2 is a front elevational view of the chessboard,
FIG. 3 is a side elevational view of the chessboard, and
FIG. 4 is a plan view of the chessboard.

We claim:

The ornamental design for a three dimensional staggered chessboard with movable supports for chessmen, as shown.
